UNITED STATES PATENT OFFICE.

WILLARD R. GREEN, OF MUSCATINE, IOWA.

ABSORBENT MATERIAL.

No. 810,137.

Specification of Letters Patent.

Patented Jan. 16, 1906.

Application filed July 25, 1904. Serial No. 217,970.

To all whom it may concern:

Be it known that I, WILLARD R. GREEN, a citizen of the United States, residing in Muscatine, in the county of Muscatine and State 5 of Iowa, have invented certain new and useful Improvements in Absorbent Materials, of which the following is a specification.

This invention relates to and has for its object to provide an improved absorbent material for hygienic and surgical purposes.

In the drawings accompanying and forming a part of this specification, Figure 1 is a perspective view of a portion of an absorbent body made in accordance with the present 15 improvement. Fig. 2 is a sectional view of the mass of absorbent material. Fig. 3 is a similar view showing surfacing layers of fiber applied to the top of the mass. Fig. 4 shows surfacing applied to both sides, but respectively of different character. Fig. 5 shows fine surfacing applied to the under side. Fig. 6 is a perspective view of the material scored or partially severed to permit of the ready removal of portions for use. Fig. 7 is a perspective view of similar material in a roll and 25 partially unrolled. Fig. 8 is a view illustrating the mode of application of a portion of this material, and Fig. 9 is an end view of a roll of the material.

My present invention relates to absorbent materials, the object being to provide an absorbent mass comprising different kinds of strands and fibers, these being so combined or organized together as to provide a relatively high capillary absorptive power and at the same time to permit the use in the manufacture of absorbent material of relatively coarse strands, also to provide such a material adapted to take up and retain relatively 35 large quantities of fluid without becoming matted or felted, thus adapting the material for an extended range of uses, while providing for the manufacture of the same at a relatively low cost.

In the enlarged or magnified view, Fig. 2, a small portion of the absorbent material is illustrated to be composed of two kinds of absorbent mingled together, one kind consisting of relatively large and more rigid 45 strands, as 6, and the other kind consisting of relatively fine and more flexible fibers, as 8, distributed through the interior of the mass within spaces, as 9, formed by the relatively rigid strands 6, whereby the rigid strands 50 keep open and expanded the finer fiber component of the mass and whereby the two

kinds of absorbent together form the capillary and fluid-retaining spaces or interstices of the mass. While different kinds of fiber products may be employed for the coarser 60 component—such, for instance, as certain small plants or grasses suitably crushed or otherwise prepared—I prefer to employ for such coarser component a woody body in the nature of small strands, these being preferably of a flat and narrow or ribbon-like form, and preferably also of varying sizes intermingled together so as to form interiorly thereof fluid receiving and retaining spaces. The larger of these spaces serve as conducting 70 spaces in the nature of conduits for distributing the fluid through the interior of the mass and conducting the same to the small capillary or retaining spaces formed in the completed mass by the intermingling of the fiber 75 and strands.

For the fiber I prefer to use a relatively flexible and yielding vegetable fiber—such, for instance, as cotton or linen. This fiber is distributed through the mass and extends between and is intermingled or intermeshed with the coarser and more rigid strands, which in a sense form a supporting member or mass component for normally holding the mass as a whole in a properly-expanded form 85 and prevent the same from undue compression. For these coarser components or strands I preferably employ wood in the form of ribbon-like strands, which, as I have discovered, are by reason of their physical form 90 and composition peculiarly suitable for use in this kind of material, since they are relatively rigid and of highly stable form, even when the mass is wetted to saturation, besides being relatively non-felting, and therefore not liable 95 to become so packed or matted together as to essentially injure the absorptive efficiency of the mass.

In the preferred and most complete form 100 of my improved absorbent material and body portion of the mass (designated in a general way by 10) has the filament component thereof extended outside of the commingled mass of strands and the finer filament material to form a surfacing finish for the purpose, among others, of giving the surface of the material, especially when this is in sheet form, a soft finish and at the same time not make the surface portion of the mass so dense 105 as to prevent rapid absorption through the thin and loosely-formed fiber surface or bat into the interior spaces of the mass. In this

connection it will be remembered that in the case of ordinary absorbent vegetable fiber—such, for instance, as absorbent cotton as ordinarily prepared and used—a small amount 5 of fluid, especially if it be not perfectly liquid, tends to make the surface part or the fiber pack together and become so matted (in a certain sense partially felted) as to close the inlet spaces or interstices, and thus retard 10 the passage of the fluid through the surface portion of the mass to the interior thereof. This difficulty is in many cases so great as to practically preclude the use of absorbent cotton for the purpose of taking up fluids and to 15 preclude the successful employment of such absorbent materials for many uses where they could otherwise be well adapted.

For the reasons here indicated I deem it preferable in practice to provide the absorbent mass with a filamental surface portion upon one or both sides of only a small thickness, but sufficient to give a smooth and soft finish to the same, and to provide the absorbent mass, this being preferably made in 20 the form of a sheet or bat of moderate thickness, (designated in a general way by 10,) on one side thereof with a filamental surface sheeting, as 13, consisting of fiber or fiber-stock—such, for instance, as short fiber paper- 25 stock combined with a small amount of cementitious material, sufficient in quantity, however, to cause this fiber member of the mass to normally retain its continuity after the major portion of the mass has been divided by cutting into blocks, as 12, of a size 30 convenient for use. This finer material is more fully illustrated in connection with Figs. 1, 4, 5, 6, and 9, in which is represented a sheet of the material provided on one side 35 with the loosely-matted filamental surfacing portion 11 and on the other side with the cementitious fiber surface 13 for temporarily holding the divided portions 12 of the mass together until the same are required for use. 40

In Fig. 9 the advantages of the described mode of putting up and packing the material are illustrated. The roll of material having its usual casing, as 14, Fig. 7, torn off, one end 45 of the sheet may then be unrolled for a short distance, (or may be left on the surface of the cylinder or package,) and the user may by taking hold of one end of one of the incipiently-divided blocks, as 12, tear the same out of the sheet. In doing this it is only necessary to tear apart the hitherto unbroken or only partially-broken cementitious fiber 50

layer 13. The block or portion torn out from the sheet may be taken in the fingers and used in the same manner as any small mass or bunch of absorbent fiber and is especially adapted for being folded up—as illustrated, for instance, in Fig. 8—so that the outer filament surface of the sheet or mass will form a continuous surface with which to touch a wound, for instance, as required 60 for use in surgical operations and the like. This mode of folding the thin block or small sheet for use normally forms the same into a suitably covered and kneaded surface well adapted for effective use. 65

The absorbent material herein shown and described is for hygienic and surgical purposes in the form of bandages or otherwise, and the term "surgical purposes" in the claims is intended to cover such uses. 70

Having thus described my invention, I claim— 75

1. As an article of manufacture, an absorbent body for surgical purposes consisting of a main portion composed of woody strands and 80 one or more surface layers composed of fiber.

2. As an article of manufacture, an absorbent body for surgical purposes consisting of a main portion composed of a mixture of excelsior and fiber, and one or more surface layers 85 of fiber upon said mass.

3. As an article of manufacture an absorbent mass for surgical purposes consisting of a main portion comprising intermingled woody strands of various sizes, and a surface layer 90 composed of vegetable fiber, such as cotton or linen fiber.

4. An absorbent material for surgical purposes consisting of a highly-absorbent mass of mixed strands and fiber, and a surfacing of 95 cementitious fiber upon one side, and a vegetable fiber upon the other side.

5. As an article of manufacture, an absorbent mass for surgical purposes consisting of a body made up of intermingled woody strands 100 or ribbons of various sizes, and a fibrous or filamentous surface layer on one or more faces thereof, the whole arranged in sheet form and partially divided into blocks or sections to permit ready detachment thereof. 105

Signed at Nos. 9 to 15 Murray street, New York, N. Y., this 27th day of June, 1904.

WILLARD R. GREEN.
